UNITED STATES PATENT OFFICE.

NICHOLAS C. ORRICK, OF CANTON, MISSISSIPPI.

ROPE-CLAMP.

SPECIFICATION forming part of Letters Patent No. 252,502, dated January 17, 1882.

Application filed November 25, 1881. (No model.)

To all whom it may concern:

Be it known that I, NICHOLAS C. ORRICK, of Canton, in the county of Madison and State of Mississippi, have invented certain new and useful Improvements in Rope-Clamps; and I do hereby declare that the following is a full, clear, and exact description of the invention, which will enable others skilled in the art to which it appertains to make and use the same, reference being had to the accompanying drawings, which form a part of this specification.

Figure 1 is a perspective view, illustrating the parts constituting my improved rope-clamp detached from each other. Fig. 2 is a longitudinal vertical sectional view. Fig. 3 is a vertical cross-section, and Fig. 4 is a perspective showing a modification.

Corresponding parts in the several figures are denoted by like letters of reference.

20 This invention relates to clamps for the ends of rope traces and for similar purposes; and it consists in certain improvements in the construction of the same, which will be hereinafter fully described, and particularly pointed out in the claims.

In the drawings hereto annexed, A and B represent two semi-cylindrical shells or parts, constituting the body of my improved rope-clamp. One of said parts, A, is provided at 30 its rear end with an eye or opening, C, to receive a hook or link for attachment to the whiffletree or to the hame-hook, as the case may be. Directly in front of the eye C is formed an undercut recess, D, which forms 35 part of a hinge-joint.

The shell or part B is provided at its rear end with a diagonally downward and rearward projecting tongue, E, adapted to fit in the recess D of part A, and enabling the shell B to 40 turn as upon a hinge in relation to the said part A. The latter is provided upon its sides with studs F, forming guides, which fit in recesses G in the sides of shell B, thus causing the parts to fit nicely and securely together without danger of lateral displacement.

The shells or parts A and B are provided with inward-projecting sharp points or prongs, H, and one or both of said parts is provided, upon the outside, near the front end, with a 45 nib or stud, I.

J is a metal ring having one or more slots or notches, K, corresponding with the stud or studs I, over which the said ring may be slid upon the end of the clamp after the parts of the same have been joined. By partly turning 55 the ring J the same is then retained in position, securely locking the parts A B together.

The shells A and B are provided at their rear ends with screw-threads R, as shown. These threads serve to clamp the fibers of the 60 rope transversely, thus taking the place of the binding with twine usually employed to prevent the ends of the ropes from unraveling, and which by my improvement may be omitted, thus saving time and trouble. 65

In Fig. 4 of the drawings I have shown a modification of my invention which consists in omitting the guide-studs F and their corresponding recesses, and in lieu thereof extending the sides of the lower shell, A, upward at 70 the rear end and correspondingly beveling the rear end of shell B. This construction is more compact, and a similar result is achieved.

The operation of my invention will be readily understood. The end of the rope is placed 75 in the semi-cylindrical shell A, the points or prongs H of which are driven through it. The tongue E of shell B is then placed in recess D of shell A, and shell B is then gradually lowered as if turned upon a hinge until its points 80 H pierce the rope and the shells or parts A and B fit closely together. The ring J, which may have been previously adjusted upon the rope, is then slid upon the end of the clamp and partly turned, thus locking or binding the 85 parts A B securely together.

With my improved clamp a light, inexpensive, and very durable rope trace may be constructed. The clamp, at the front end of the trace, is to be provided with several links for 90 attachment to the hame-hook, and by shifting the said links in the usual manner the trace may be lengthened or shortened, as required.

I wish it to be understood that I do not confine myself to the use of the ring J for securing 95 the parts A B together, as many other devices may be successfully used for the same purpose. I have selected this method, however, as being simple and effective.

Having thus described my invention, I claim 100

and desire to secure by Letters Patent of the United States—

1. As an improvement in rope-clamps, the combination of the shell A, having eye C, recess D, and prongs H, with the shell B, having tongue E and prongs H, substantially as and for the purpose set forth.

2. As an improvement in rope-clamps, the semi-cylindrical shells A, B, having prongs H and provided respectively with a recess, D, and tongue E and with guides F and recesses G, substantially as set forth.

3. In a rope-clamp, the combination, with the shells A, B, constructed substantially as described and having stud or studs I, of the

ring J, having notch or notches K, corresponding with said studs, as set forth.

4. The combination of the shells A, B, having respectively recess D and guides F, and tongue E and recesses G, both of said shells being provided with prongs H and screw-threads R, substantially as set forth.

In testimony that I claim the foregoing as my own I have hereto affixed my signature in presence of two witnesses.

N. C. ORRICK.
